US00D818799S

(12) **United States Design Patent** (10) Patent No.: **US D818,799 S**
(45) Date of Patent: **** May 29, 2018**

(54) **WALL MOUNTED JACK PANEL**

(71) Applicant: **Crestron Electronics, Inc.**, Rockleigh, NJ (US)

(72) Inventors: **André Poulheim**, Frechen (DE); **Stefan Kenta Hohn**, Cologne (DE); **Evan Ackmann**, Hoboken, NJ (US)

(73) Assignee: **Crestron Electronics, Inc.**, Rockleigh, NJ (US)

(**) Term: **15 Years**

(21) Appl. No.: **29/612,131**

(22) Filed: **Jul. 28, 2017**

(57) **CLAIM**

The ornamental design for a wall mounted jack panel, as shown and described.

DESCRIPTION

FIG. 1 shows a front perspective view of a wall mounted jack panel.

FIG. 2 shows a front elevation view of the wall mounted jack panel.

FIG. 3 shows a left side view of the wall mounted jack panel.

FIG. 4 shows a right side view of the wall mounted jack panel.

FIG. 5 shows a top view of the wall mounted jack panel; and, FIG. 6 shows a bottom view of the wall mounted jack panel. The broken lines in the figures depict portions of the wall mounted jack panel that form no part of the claimed design.

1 Claim, 4 Drawing Sheets
